DESIGN FOR A LADY'S COLLAR

Ernest Gold, New York, N. Y.

Application July 29, 1939, Serial No. 86,321

Term of patent 3½ years

To all whom it may concern:

Be it known that I, Ernest Gold, a citizen of the United States, residing in the city, county, and State of New York, have invented a new, original, and ornamental Design for a Lady's Collar, of which the following is a specification, reference being had to the accompanying drawing, forming part thereof.

Figure 1 is a front elevation of a lady's collar showing my new design applied thereto; and

Figure 2 is a rear elevation thereof.

The characteristic feature of my design resides in the combination, on the collar disclosed of braided loops secured to the lower edge thereof and a chain threaded through said loops and extending beyond the ends of the collar to form pendent loops as shown.

I claim:

The ornamental design for a lady's collar, substantially as shown and described.

ERNEST GOLD.
